UNITED STATES PATENT OFFICE.

GEORGE W. OUSLEY, OF SAN FRANCISCO, CALIFORNIA.

WINDOW-WIPE.

1,165,704.

Specification of Letters Patent. Patented Dec. 23, 1915.

Application filed November 23, 1914. Serial No. 673,476.

To all whom it may concern:

Be it known that I, GEORGE W. OUSLEY, a citizen of the United States, residing in the city and county of San Francisco and State of California, have invented new and useful Improvements in Window-Wipers, of which the following is a specification.

This invention relates to window cleaning devices.

It is an object of this invention to provide a means operative at one time on both sides of a pane of glass in a window to remove condensed moisture therefrom.

The invention consists of the parts and the construction and combination of parts as hereinafter more fully described and claimed, having reference to the accompanying drawing, in which—

Figure 1 is a perspective view of the device as installed. Fig. 2 is a sectional view of a sash showing the cleaner in elevation. Fig. 3 is a detail sectional view through the spring socket. Fig. 4 is an edge view of the wiper.

2 indicates a pane of glass in a sash 3 which may be erected in a car, engine cab, pilot house, look-out station, or sentry box, and in which instances it is very desirable and necessary that the glass be kept clear of condensed moisture from any source. No difficulty is experienced as to keeping the inside surface of a window clear by simply running a hand or a piece of convenient material over it, but this is not as easily done 35 on the outside surface, and, even so, requires the opening of the window sometimes in a driving rain. By my present invention both sides of the glass are simultaneously cleansed without opening the window and by a single 40 movement of the operator or attendant at the station.

The device comprises a pair of arms 4—5, the former having a short trunnion 6 to project through a hole in the window sash 45 for non-turnable attachment to the adjacent end of the companion arm 5. The trunnion is turnable in the sash and has a screw thread 7 to receive a nut 8 for clamping up the arm 5. The upper ends of the arms 4—5 50 are laterally offset, as at 9—9, and bent back at right angles to form parts 10—10 which lie close to the sash 3. When trunnioned in the sash, the arms 4—5 stand out from and parallel with the glass 2 and in the space on 55 each side of and against the latter lie wipers, each consisting of a cleaning strip

11 which may be of any suitable character, here shown as flat wick folded over a core 12 and clamped in a channel clamp 13. This clamp has spaced pairs of opposite lugs 14, 60 the ends 15 of which telescope in slides 16 having pockets 17 with springs 18 reactive against the lugs to force the cleaning strip 11 against the glass. The slides 16 have rectangular chambers 19 to fit and slide upon 65 similarly shaped portions of the arms 4—5 to hold the wipers firmly toward the glass. In order that the cleaning strip may be readily renewed without dismantling the whole device, the arms are provided with 70 rounded portions 20—21, the latter being threaded to receive a lock-nut 22. By retracting the nut 22 this allows the lower slide 16 to move down onto the round 22 and the upper slide is pulled down by the 75 clamp 13, which interconnects the slides, through its relation at the lugs 14 in the sockets. When the slides 16 on one arm are at the rounded portions thereof the clamp 13 may then be swung around away from the 80 glass and the strip 11 removed, a fresh one inserted and the clamp swung back and forced up to lift the slides along the arm 85 and onto the square parts. The nut 22 is then advanced to lock the lower slide in the upper position, Fig. 2.

When the arms 4—5 are assembled parallel in a common plane and on opposite sides of a window glass, they may then be swung up or down together by the operator, the 90 wipers 11 bearing firmly throughout their length on the sides of the glass. A single sweep over the surfaces serves to effectually remove the translucent condensation and leave the window clear. To hold the cleaner 95 in one or another of its positions, one or more springs clips 23 may be provided.

Having thus described my invention, what I claim and desire to secure by Letters Patent is—

1. In a window cleaner, a pair of arms adapted to be arranged on opposite sides of a window pane, means to both connect the arms at one of their ends and to provide a pivotal mounting for the arms, spaced upper and lower lateral inwardly extending hollow members on the end portions of the arms, a clamp for each arm, said members having interior side pockets, lugs on the clamps extending into the respective pockets, coil springs in the pockets engaged with the lugs to normally force the clamps out- 105 110

wardly, and cleaning strips connected to the clamps.

2. In a window cleaner, an arm having a flat side and spaced portions of circular cross section, one of the circular cross section portions being screw threaded, a pair of lateral members each being formed with an opening to slidably receive the arm, said members being adapted for rotary movement on the circular cross section only of the arm, a cleaning element detachably car-

ried by the lateral members, and a nut member engaged on the threaded portion of the arm for supporting the lateral members on the flat side portion of the arm.

In testimony whereof I have hereunto set my hand in the presence of two subscribing witnesses.

GEORGE W. OUSLEY.
